THOMAS L. SMITH, OF MILWAUKEE, WISCONSIN.

ROCK-CRUSHER.

1,075,507.

Specification of Letters Patent. Patented Oct. 14, 1913.

Application filed November 6, 1911. Serial No. 658,675.

To all whom it may concern:

Be it known that I, THOMAS L. SMITH, of the city of Milwaukee, State of Wisconsin, have invented certain new and useful Improvements in Rock-Crushers, of which the following is a specification.

My invention relates to improvements in rock crushers and it consists of the novel construction, combination and arrangement 10 of parts hereinafter shown, described and claimed.

In the accompanying drawing which forms a part of this specification, Figure 1 shows a central vertical section through the 15 machine and Fig. 2 shows a cross section through part of the device taken on the line L. L. of Fig. 1.

Referring to the parts of the device by numbers, 10 is the stationary die of the 20 crusher supported in the frame 11.

12 is the oscillating jaw hung on the pivot shaft 13 and carrying the moving die 14.

The eccentric shaft 15 is journaled in the frame, said journals being shown by the 25 dotted circle 16, and carries the eccentric sleeve 17. The rib 18 projecting from the eccentric sleeve, is the means through which the eccentric 15 actuates the movable jaw 12 to swing on the pivot shaft 13. The rib engages 30 the movable jaw 12 intermediately through the block 19 which is adjustable along the rear face of the jaw 12 in a groove shown in Fig. 2, the sides of which are designated by the numerals 20 and the bottom 35 thereof by 26. This adjustment of the block is effected by the screw 21 which engages screw threads in the upper part of the block as shown in Fig. 1. The screw is rotatable in the lug 23 of the jaw 12, is held against 40 longitudinal movement in said lug by the head of the screw and the set collar 24, and is held in its adjusted position by the set screw 25.

When the eccentric 15 is revolved in the 45 operation of the machine, the point of engagement of the rib 18 with the block 19 will swing in a short arc around the center of the pivot shaft 13. The longer the radius of this arc is made by moving the block 50 19 away from the shaft 13, the less will be the angular movement of the jaw 12. Also, when the line through the center of the journals 16 and the point of engagement of

the rib 18 with the block 19 is perpendicular to the surface of the jaw 12 on which the block 19 is adjustable, the jaw will be at its maximum distance from the eccentric, and any movement of the point of engagement to increase this angle will allow the jaw 12 to approach the eccentric and will also decrease the length of movement of the engaging point in the arc around the center of the pivot shaft 13. The opening between the dies can therefore be adjusted by movement of the block 19 even when the surface 65 26 of the jaw on which the block bears is parallel to the face of the die 14, and even if the surface 26 were curved around the eccentric. It is preferable, however, to make this surface plain for ease of construction 70 and convergent with the face of the die toward its free end for rapidity of adjustment.

In the preferred form as shown the block 19 is at the maximum upward adjustment 75 to produce the smallest size of crushed product. Any downward movement of the block 19 will increase the opening between the dies 10 and 14 and increase the size of the product. It will also incidentally increase the leverage of the point of application of the 80 power from the fulcrum which is the shaft 13.

As the size of product required is frequently changed, it is desirable to effect the necessary adjustment as readily and with as 85 little delay as may be. With this improved device all adjustment is effected by merely loosening the set screw 25, turning the screw 21 until the block 19 is in the required new position, and securing the screw 21 again 90 by the set screw 25, all of which may be done while the machine is running.

What I claim as my invention is—

In a rock crusher, a stationary jaw and a movable jaw arranged with a tapering space 95 therebetween through which the rock passes by gravity as it is crushed, a shaft above the receiving end of said space movably supporting said movable jaw, a bearing block on the side of said movable jaw opposite 100 its crushing surface and near its discharge end, means for adjusting said bearing block along said jaw to or from its discharge end, and an eccentric shaft and sleeve thereon 105 for actuating said movable jaw, said sleeve and bearing block having a rocking engage-

ment with each other, the path of adjustment of said bearing block being inclined to the shortest distance between the center of the eccentric shaft and the crushing surface of the movable jaw and converging with said crushing surface toward its discharge end.

In testimony of which, I hereunto affix my hand, in the presence of two witnesses.

THOMAS L. SMITH.

Witnesses:

LILLIE SCHUMACHER,
A. B. SCHMITZ.
